UNITED STATES PATENT OFFICE.

JOHN M. SEMPLE, OF ATTLEBORO, MASSACHUSETTS, ASSIGNOR TO THE
B. K. MANUFACTURING COMPANY, OF RHODE ISLAND.

PIN-JOINT.

SPECIFICATION forming part of Letters Patent No. 674,023, dated May 14, 1901.

Application filed December 13, 1900. Serial No. 39,689. (No model.)

To all whom it may concern:

Be it known that I, JOHN M. SEMPLE, a citizen of the United States, residing at Attleboro, in the county of Bristol and State of Massachusetts, have invented a certain new and useful Improvement in Pin-Joints, of which the following is a specification, reference being had therein to the accompanying drawings.

My invention relates to the pin tongue, joint, and post of ornamental pins or brooches, and has for its objects the improved appearance of the finished joint, a stable construction of the parts, an improved tension for the pin-tongue, and a minimum number of parts, with a resulting decrease of expense and labor.

Heretofore in applying pin-tongues to pins or brooches of irregular body formations it has been necessary to solder the common forms of pin-sockets to the top of a block and next solder the latter to the body to bring the pin-joint into a position parallel to the plane of the rear surface of the body. Sometimes the block is used even on bodies having a smooth rear contour in an attempt to thereby create a tension upon the pin-tongue. Such constructions are obviously weak, laborious, and expensive.

To the ends first above enumerated my invention consists in the novel construction and arrangement of parts hereinafter described, and illustrated in the accompanying drawings, wherein—

Figure 1 is a side elevation of my improved pin-joint applied to a crescent or knot pin. Fig. 2 is a plan view of the pin-tongue blank; Fig. 3, a side view of the same with completed base; Fig. 4, a side elevation of the post and pin; and Fig. 5 is a transverse vertical section of the engaged tongue and post on line xx of Fig. 1.

Like letters refer to like parts throughout the several views.

The construction and assemblage of parts are as follows: A pin-tongue blank A is constructed with lateral lugs or ears bb projecting from its end at right angles to the pin-point a . The ears bb are folded with their extremities approaching each other to form an arched or cup-shaped base, as shown in

Figs. 3 and 5. The pin-tongue thus constructed is mounted upon the upper portion of a post c by means of a pin d , which traverses said post and the members bb of the tongue-base. The pivotal engagement thus effected furnishes a bearing for the point a upon the top e of the post c when the point a is in the engaged position. (Shown by broken lines in Fig. 3.) In order to afford a pronounced spring or tension for the pin-tongue A, I prefer to make the upper post-surface e slightly inclined and continue the same to form a fulcrum projection or toe i to meet the downward pressure of the pin-tongue when the latter is forced into its catch m , Fig. 1. The post c may be struck up in quantities and of any convenient length. The lower ends thereof are then cut off at whatever length is most convenient to meet the irregularities of the bodies to which they are respectively intended to be applied. The post c is soldered to the pin-body B, as shown in Fig. 1, and the catch m affixed in the usual manner.

Having thus described my improved joint, what I claim as new, and desire to secure by Letters Patent, is—

In a pin-joint of the class described, the combination with the ornament or equivalent body, of a post rigid at one end with said body and provided at its other end with an inclined bearing-surface formed with a fulcrum projection, the pin-tongue consisting of a single blank provided at one end with an integral laterally-expanded flattened portion bent to produce offset ears constituting an arched base straddling the post, and coöperating with said inclined bearing-surface and the fulcrum projection thereof, said inclined bearing-surface lying within the longitudinal plane of the pin when fastened and disposed outwardly from the ornament or equivalent body, and a pivotal connection between said ears and the post.

In testimony whereof I have affixed my signature in presence of two witnesses.

JOHN M. SEMPLE.
